COIN HOLDER

Nels H. Swanson, Chicago, Ill.

Application November 16, 1933, Serial No. 698,268

9 Claims. (Cl. 133—9)

The purpose of this invention is to provide a coin holder arranged for receiving and retaining coins of different denominations in distinguishable groups, and adapted to be carried in the 5 pocket or handbag of the user; and to provide such coin holder with means for safely retaining the coins in their respective groups against accidental escape from the holder or intermingling of the different groups in the holder; and to facilitate selection and withdrawal of individual coins 10 from any group without necessity for visual inspection.

The invention consists in the elements and features of construction shown and described as indicated in the claims.

In the drawing:

Figure 1 is a perspective view of the coin holder embodying this invention.

Figure 2 is a direct top plan view of the same. 20 Figure 3 is an inverted or bottom plan view.

Figure 4 is a vertical section at the line 4—4 on Figure 2.

Figure 5 is a detail section at the line 5—5 on Figure 2.

Figure 6 is a front elevation showing the holder mounted on a flexible sheet, as a wrapper or the 25 wall of a handbag.

Figure 7 is a detail section at the line 7—7 on Figure 6.

Figure 8 is a plan view of the sheet metal blank from which the body of the holder is formed.

Referring to the drawing in detail:

The coin holder comprises a sheet metal stamping indicated in entirety at A, and consisting of 35 a back member, 10, which is continuous from end to end of the holder forming a back-wall-in-common to the four coin-receiving cells seen at A, B, C and D, and indicated as containing respectively quarters, dimes, half dimes and copper 40 cents.

The blank shown in Figure 8 is formed with 45 projections 11, 11, 11 at right angles to the portion which constitutes the back-wall-in-common, which projections in the finished device are each folded at right angles to form bottom elements, 12, and front wall elements, 13^a, 13^b and 13^c of the cells, said bottom elements and said front wall elements being very substantially spaced apart, as shown at 14 with respect to the bottom elements, 50 and at 15 with respect to the front wall elements. And it will be noted that by thus spacing apart the front wall elements, they are renderedlapping over adjacent portions of the consecutive cells occupied by corresponding segments of the 55 coins in the respective cells. Opposite end por-

tions of the back-wall-in-common of the blank are folded at right angles first forwardly and then inwardly, as seen at 17 and 18 in Figure 2 to form end walls and front wall elements of the extreme cells, A and D. For partitioning the consecutive 60 cells from each other there are provided vertical partitions, 20^a, 20^b and 20^c, inserted between the back-wall-in-common, and the other wall elements 13^a, 13^b and 13^c, midway in the width of said front wall elements, said partitions being secured permanently, as by riveting to the back-wall-in-common, as seen at 21^a, and to the front wall elements respectively, as seen at 21^b, and also preferably to the bottom elements, as seen at 21^c.

Upon considering the construction as thus far described, it will be noted that the total width of the several cells is the distance between the end walls, 17 and 18, and the partitions, 20 and 20^c, respectively in the case of the end cells, A and D, 70 and is the distance between the partition, 20^b and the partitions, 20^a and 20^c, respectively in the case of cells, B and C; and that these widths are different according to the dimensions of the coins to be accommodated in the respective cells, as cell 75 A being dimensioned to receive silver quarters, cell, B, for silver dimes, cell, C, for nickels, half dimes, and cell, D, for copper cents. And it will be further noted that the cell bottoming elements, 12, in each instance serve for bottoming two consecutive cells, and that similarly the front wall elements, 13^a, 13^b and 13^c, each constitute the front wall element of two consecutive cells, this double 80 functioning of the bottoming element and front wall elements being due to the mounting of the 85 partitions midway in the width of the front wall element and bottoming elements.

For retaining the coin safely in the respective cells against accidental escape, there is provided at one edge of each cell a resilient retainer, 30, 90 lodged at its lower end on the bottom element of the cell and extending up alongside the partition and having its upper end portion flexed apart from the partition, as seen at 30^a, to overhang a lateral segment of the coin in the cell and stress them 95 toward the opposite edge wall of the cell.

Since such resilient retainer is required only at one side of each cell, it is convenient to provide retainers at opposite sides of the partitions, 20^a and 20^c, leaving partition, 20^b, without an immediately associated retainer; and the opposite side wall toward which the coins are stressed in the case of cells A and D, are the walls, 17 and 18, and in the case of the cells, B and C, are opposite 100 sides of the partition, 20^b. And in view of this 105 110

arrangement of the resilient retainers at opposite sides of the partitions, 20^a and 20^c, it is convenient and preferable to make the retainers which are thus placed at opposite sides of the 5 partition integral with each other, as seen in Figure 1, the junction portion, 30^a, being lodged on the bottom element and formed with a rivet-accommodating aperture, 30^b, through which the riveting tenon, 22^c, of the partition extends for 10 binding the couple of integral resilient retainers fast to the bottom and to the partition.

For facilitating the insertion of the coins into the cells, the resilient retainers, 30, are each formed at the upper end by bending outwardly 15 with respect to the cells to present a bevel or face sloping inwardly with respect to the cell, as seen at 30^c; and to accommodate these outwardly projecting bends, 30^c, when in the insertion of a coin the resilient retainer is forced out to flat position 20 against the partition, 20^a, the partition is terminated at the upper end slightly below the upper edge of the back wall, 17, which at that part of its extent properly extends to the full height of the resilient retainer to guard and guide the 25 edge of the latter in its resilient reaction in the insertion and withdrawal of the coins.

The holder, as shown in Figure 1, is suitable for carrying in the pocket of the user without enclosure or wrapper, but it may be preferred in some 30 instances to provide it with a wrapper, and in other instances to mount it on the wall or partition of a handbag or purse; and for such purpose the back-wall-in-common is formed with eyelet holes, 35, at least two of the cells, said eyelet holes 35 being countersunk, preferably in the stamping process, at the inner side, as seen at 35^a, to avoid protrusion of the head of the securing eyelet or other form of fastening into the coin space of the cell. The wrapper or partition of the handbag to 40 which the holder may be attached as described, is indicated at 40.

Upon considering the construction as shown and described, it will be noted that between consecutive cells, A and B, and between consecutive 45 cells, C and D, there are interposed for partitioning the two cells, not only the element referred to as a partition, but also further partitioning means consisting of the pair of resilient coin retainers. But I do not limit myself to employing 50 both these partitioning means, and the rigid partitions may be dispensed with without departing from the main invention.

I claim:

1. A coin holder having a plurality of cells for 55 receiving and retaining different denominations of coins arranged consecutively edge to edge in a row in distinguishable groups, said holder comprising a back-wall-in-common to all the cells and a bottom element for the several cells extending 60 from the bottom edge of the back wall, and a front wall element for the cells extended therefrom parallel to the back-wall-in-common; partitions between the consecutive cells extending 65 between the front wall element and the back-wall-in-common and extending upwardly from the bottom element, and resilient coin retainers mounted on the bottom element and extending upwardly therefrom adjacent to and slightly spaced longitudinally of the holder from the partitions respectively, said resilient coin retainers being flexed away from the partitions inwardly 70 with respect to the respective cells at a part of their length at which they extend past the center of the coins for which the cells are respectively dimensioned; whereby said retainers en-

gage the coins yieldingly against withdrawal edge-wise from the respective cells.

2. The construction defined in claim 1 having a back-wall-in-common at the opposite ends formed by bending forwardly and then inwardly 80 to form outer edge walls and front wall elements of the opposite end cells of the row.

3. A coin holder having a plurality of cells for receiving and retaining different denominations of coins in distinguishable groups, said holder having a back wall continuous over all the cells, front wall members; a cell bottoming element rigidly joining the front wall members to the back-wall-in-common and rigid partitions between the consecutive cells rigidly joined to the bottom element and rigidly extending respectively between the back wall and the several front wall members at positions midway in the width of the respective front wall members, and resilient coin retainers mounted at one end on the bottom element for extending up therefrom alongside the several partitions at opposite sides of the latter toward the respective cells which are separated from each other by said partitions, each of said retainers at the upper part of its 100 length being flexed away from the partition alongside which it extends inwardly with respect to the cell to overhang a lateral segment of the coins carried in the cell.

4. The construction defined in claim 3, the partitions being formed at the lower end and at front and rear edges at the upper end with tenons for riveting to the bottom element and to the back wall and to the front wall members respectively, and the resilient retainers being formed at their 105 lower ends for being engaged between the lower ends of the respective partitions and the bottom element, whereby said retainers are secured in their mounting on the bottom element by the riveting of said partitions to said bottom element. 110

5. The construction defined in claim 1, the resilient retainers each having the upper edge portion flexed toward the partition adjacent to which it is mounted for presenting a beveled face toward the coin inserted in the cell, the partitions being 115 each terminated at the upper end below the upper edge of the back wall and below the flexed upper end portion of the retainer to accommodate the said end portion within the height of the back wall when the retainer is stressed to flat position against the partition in the insertion of a coin.

6. The construction defined in claim 1, the resilient coin retainers being mounted as called for in said claim 1 adjacent alternate partitions 120 and at opposite sides of said alternate partitions respectively, the other alternate partitions being without adjacent resilient retainers, whereby each cell is equipped with a resilient retainer at one side only.

7. A coin holder having a plurality of cells arranged consecutively edge to edge in a row for receiving and retaining different denominations of coins in distinguishable groups, said holder having back, bottom and front wall elements 130 formed integrally from a sheet metal blank, the back wall being continuous over all the cells, the blank being formed with relatively narrow strips projecting from the bottom edge of said continuous back wall portion at points in the length 135 of the holder corresponding to the meeting edges of the consecutive cells, each strip being folded at right angles to form first bottom elements and then front wall elements of two consecutive cells, and partitions separating consecutive cells 140

145

150

- interposed between the back wall and the front wall elements midway in the width of the front wall strips respectively and secured permanently to the back wall and to the bottom and front wall elements, alternate partitions having mounted at opposite sides resilient coin retainers secured at their lower ends between the bottom elements and the partition, and at their upper part spaced from the partition and flexed away 5 therefrom for overhanging a lateral segment of the coins in the cell.
8. A coin holder having a plurality of cells for receiving and retaining different denominations of coins arranged consecutively edge to edge in a row in distinguishable groups, said 10 holders comprising a back-wall-in-common to all the cells and a bottom element for the several cells extending from the bottom edge of the 15 back-wall-in-common and a front wall element for the cells extending from the forward edge of the bottom element parallel to the back-wall-in-common; a pair of resilient coin retainers interposed between consecutive cells, the individuals of said pairs having their upper end portions flexed laterally inwardly with respect to the respective cells for overhanging each a lateral segment of the coins carried in the cell.
9. The construction defined in claim 3, the front wall of each cell consisting of two parts lapsing respectively opposite segments of the coin-accommodating space of the cell and spaced apart over the intermediate segment of said coin-accommodating space for exposure of a special 20 part of the face of the coin for identification of the coin and grasp thereof for removal.
